Cooper, Kerr & Dunham

UNITED STATES PATENT OFFICE.

JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK.

INTERLOCKING SYSTEM FOR DOOR LOCKS AND THE LIKE.

Application filed August 27, 1924. Serial No. 734,385.

To all whom it may concern:

Be it known that I, JAMES W. BRYCE, a citizen of the United States of America, residing at Bloomfield, in the county of Essex and State of New Jersey, have invented certain new and useful Improvements in Interlocking Systems for Door Locks and the like, of which the following is a full, clear, and exact description.

- 10 This invention relates to interlocking systems for door locks and the like. The invention finds particular utility in connection with recording locks wherein a record is made of the time of locking or unlocking 15 of the door, but it is not limited to such installations. It has heretofore been proposed to provide an interlocking device on one door so as to prevent the locking of this door until other doors or windows have 20 been properly bolted. In certain of these former systems of which Bush Patent No. 1,270,264 is an example, the circuit arrangements were such that the supplementary lock contacts were serially connected and 25 normally open with the supplementary bolts unlocked. With this system a weak or exhausted battery, a broken wire, bad contacts or dirty contacts prevented the locking of the main door lock. Furthermore the 30 current consumption was high inasmuch as current kept flowing through the system until the main lock was advanced in the event the supplementary locks were advanced and the main door closed.
- 35 In other systems such as that shown in the co-pending application of L. C. Bush, Serial No. 731,006, filed August 9, 1924, the control contacts are in multiple and normally are closed with the supplementary bolts unlocked. With a weak or exhausted battery or a broken wire the main door could be 40 locked, but if the contacts were out of adjustment or if they were dirty the system might or might not function to prevent locking 45 of the main door. Current consumption is kept low in this system.

In the present invention the control contacts are serially connected but current only flows for a short period during the locking 50 operation upon the main door. With a weak or exhausted battery the main door can be locked but a broken wire, bad contacts or

contacts out of adjustment make it impossible to lock the main door. In this way attention is called to the fact that some part 55 of the apparatus is out of order, and the defect may be remedied.

The appended drawing shows diagrammatically a preferred embodiment of my invention.

In more detail, 10 designates the main lock barrel. Fast to the lock barrel are two disks 11 and 12. Disk 11 is provided with an interlocking shoulder 13 and disk 12 is provided with a camming abutment 14. 65 Turning of the key barrel 10 actuates the bolt 15 in the usual manner. Cooperating with disk 12 and abutment 14 is a pivoted lever 16 which, upon rotation of the key barrel 10 and disk 12, is adapted to close 70 contact 17. Arranged normally out of cooperation with disk 11 is a spring withdrawn locking pawl 18 which forms a part of an armature of the interlocking magnet 19. The arrangement of parts is such that 75 if magnet 19 attracts its armature, part 18 will be shifted into the path of the lug 13 and thus prevent the complete rotation of the key barrel. There is, however, an initial partial rotation permitted of the key 80 barrel 10, to permit lever 16 to close the interlocking contacts 17 and supply the interlocking magnet 19 with current.

The contacts marked 20 are those disposed adjacent the locking bolts on windows or other doors which must be closed in order to permit the locking of the main door. These contacts 20 may be of any desired number, one being provided for each bolt 21. The arrangement of the contacts is such 90 that they are normally open and are adapted to be closed when the bolts 21 are advanced to locking position.

Circuit diagram.

22 is the battery or other source of supply. From the battery a wire 23 leads to the interlocking contact 17, from which another wire 24 leads to two opposed windings 25, 26, on magnet 19. From winding 25 a circuit 100 27 extends back to the battery 22, this circuit including a suitable resistance 28. From the further end of winding 26 the wire 29 leads to a balancing resistance 30

from the other end of which a wire 31 leads serially through the contacts 20 and back to the other side of battery 22.

Operation.

- 5 If any one or more of the contacts 20 are open the circuit through winding 26 is interrupted; consequently upon closure of contact 17 upon the attempted locking of 10 the main door, current will flow through the coil 25, attracting the armature and displacing part 18 into interlocking position. Hence it is impossible to lock the main door if any of the bolts 21 are open. 15 On the other hand, if all of the bolts 21 are advanced, thereby closing all of contacts 20, current is permitted to flow equally through the opposing windings 25 and 26 of magnet 19; consequently the armature magnet will 20 not be attracted and the main door may be locked.

In the event that the battery 22 entirely fails there will be no current in windings 25, 26, and the main door may be locked if 25 desired. If a wire in the system is broken as at X in the circuit 31, there will be an unbalancing of the current conditions in magnet 19, and this will prevent locking the door. The same action takes place if any of 30 the controlling contacts 20 are dirty.

What I claim is—

1. In an interlocking door system wherein a main lock is prevented from being locked when one or more supplementary locks are 35 unlocked, in combination with a controlling magnet and an interlocking device controlled thereby adapted to prevent the locking of the main door, controlling circuits therefor including one or more contacts normally open when the supplementary locks are 40 unlocked, a source of current for said circuits, said magnet and interlocking device having provisions for permitting the locking of the main door when the current source is 45 ineffective.

2. In an interlocking door system wherein a main lock is prevented from being locked when one or more supplementary locks are 50 unlocked, in combination with a controlling magnet, and an interlocking device controlled thereby adapted to prevent the locking of the main door, controlling circuits therefor including one or more contacts normally open when the supplementary locks are 55 unlocked, a source of current for said circuits, said controlling circuits, magnet and source of current being so related that the magnet device will operate the interlocking mechanism to prevent the locking of the main lock upon the breaking of wire in the controlling circuit.

3. In an interlocking door system wherein a main lock is prevented from being locked when one or more supplementary locks are 60 unlocked, in combination with a controlling

magnet and an interlocking device controlled thereby adapted to prevent the locking of the main door, controlling circuits therefor including one or more contacts normally open when the supplementary locks are un- 70 locked, a source of current for said circuits, said controlling circuits, magnet and source of current being so related that the magnet device will operate the interlocking mechanism to prevent the locking of the main lock 75 upon the breaking of wire in the controlling circuit, and means operative upon the attempted operation of the main locking device for supplying current to said controlling circuits.

4. In an interlocking door system wherein a main lock is prevented from being locked when one or more supplementary locks are unlocked, in combination with a controlling magnet and an interlocking device controlled thereby adapted to prevent the locking of the main door, controlling circuits therefor including one or more contacts normally open when the supplementary locks are unlocked, a source of current for 90 said circuits, said magnet and interlocking device having provisions for permitting the locking of the main door when the current source is ineffective, said contact devices and said controlling circuit being so arranged 95 that improper contact action will establish conditions which will prevent the locking of the main lock.

5. In an interlocking door system wherein a main lock is prevented from being locked until one or more supplementary locks are locked, comprising in combination with an interlocking magnet and controlling circuits therefor controlled by the supplementary locks, a source of current, and means for controlling said interlocking magnet to permit the locking of the main door upon the weakening or exhausting of said current source, said means having provisions for preventing the locking of said main lock 110 upon the breaking of a wire in said controlling circuits.

6. An interlocking door system for preventing the locking of a main lock when one or more supplementary locks are unlocked, comprising in combination, a main bolt mechanism, interlocking devices for said main bolt mechanism including a magnet having opposed windings thereon, means including circuits to said opposed windings for controlling the energization of the same, and means operative upon unbalanced current flow conditions in said opposed windings for bringing about an interlocking action upon the main bolt mechanism.

7. An interlocking door system for preventing the locking of a main lock when one or more supplementary locks are unlocked, comprising in combination, a main bolt actuating mechanism, an interlock therefor, a

magnet for operating the same, a circuit to said magnet including supplementary lock actuated contacts arranged in series and normally open when the supplementary locks are unlocked, and means for completing said circuit by and upon the manipulation of the main bolt actuating mechanism.

8. In an interlocking door system including interlocking mechanism, an interlocking magnet therefor, means operative upon a certain supply of current to said magnet for rendering the same ineffective upon the controlled interlocking mechanism and means operative upon a different supplying of current thereto for rendering the magnet effective to act upon the interlocking mechanism.

9. An interlocking door system for pre-

venting the locking of a main lock when one or more supplementary locks are unlocked, comprising in combination, a main bolt actuating mechanism, an interlock therefor, magnetic means for actuating the same, control circuits for said magnet means including circuit controlling devices adjustable by the supplementary locks and arranged to normally keep a part of the circuit open when the locks are unlocked, and a supplementary circuit controlling means adapted to temporarily supply current to said control circuits by and upon the manipulation of the main bolt actuating devices.

In testimony whereof I hereto affix my signature.

JAMES W. BRYCE.
